UNITED STATES PATENT OFFICE.

HENRIETTA L. COOPER, OF PHILADELPHIA, PENNSYLVANIA.

DESIGN FOR A PINCUSHION OR SACHET.

SPECIFICATION forming part of Design No. 22,050, dated December 6, 1892.

Application filed October 29, 1892. Serial No. 450,389. Term of patent 7 years.

To all whom it may concern:

Be it known that I, HENRIETTA L. COOPER, a citizen of the United States, and a resident of Philadelphia, Pennsylvania, have invented a new and Original Design for a Pincushion or Sachet, of which the following is a specification.

My design for a pincushion or sachet is fully illustrated in the accompanying drawing, the figure of which represents a side view of the article.

The main feature of the design is the tufted cylindrical body having rounded corners with a crown or head surmounting the same.

The body portion A of the pincushion or sachet is cylindrical in form and has at in-

tervals a series of depressions a, and mounted on the upper portion of the body is a number of short tapered pieces b of fabric, one piece overlapping another and the whole forming a head or crown.

I claim—

The design for a pincushion or sachet, as herein described and shown.

In testimony whereof I have signed my name to this specification in the presence of two subscribing witnesses.

HENRIETTA L. COOPER.
